UNITED STATES PATENT OFFICE.

REDGE HARVEY AND ADOLPH P. WASHLAKE, OF DETROIT, MICHIGAN.

DISHWASHING MACHINE.

Application filed February 23, 1923. Serial No. 620,596.

This invention relates to dish washing machines and the object of the invention is to provide a machine for washing dishes in which hot or cold water may be used and which is adapted to be connected to the usual public water supply system. Another object of the invention is to provide a machine for washing dishes comprising a spray nozzle designed to increase the velocity of water at the point of discharge therefrom, a tub being provided for the dishes into which the spray nozzle is adapted to discharge. Another object of the invention is to provide a dish washing machine having a spray nozzle which may be turned in any direction from the exterior of the tub. A further object of the invention is to provide a dish washing machine comprising a tub in which a basket for holding the dishes is rotatably mounted, the basket being made of wire and being adapted to support the dishes in spaced relation so that water may be directed to either side thereof. A further object of the invention is to provide a dish washing machine comprising a tub having a wire basket rotatably mounted therein and a spray nozzle operable from the exterior of the tub to direct water to any point on the interior thereof, the dish rack being manually rotatable from the exterior of the tub. These objects and the several novel features of the invention are hereinafter more fully described and claimed and the preferred form of construction by which these objects are attained is shown in the accompanying drawings in which—

Fig. 1 is a plan view of a dish washing machine embodying our invention partly broken away to show the construction.

Fig. 2 is a section through the dish washing machine.

Fig. 3 is a section through the spray nozzle and connections therefor.

The device comprises a tub 1 of cylindrical form as shown in Figs. 1 and 2 and is provided with a cover 2 resting on a bead 3 rolled into the upper edge of the tub. The cover 2 is provided with an opening 4 in which a pane of glass 5 is secured providing a window through which the interior of the machine may be seen. This cover 2 is provided with a pair of handles 6 by which the cover may be removed from or replaced in the tub. The tub 1 is also provided with a pair of handles 7 and a pair of supporting feet 8 shown more particularly in Fig. 2.

A tubular member 9 is secured in the bottom of the tub to provide a waterproof joint and extends upwardly into the center of the tub and a shaft 10 is rotatably mounted in the 60 said tubular member 9. A ratchet 11 is secured to the end of the shaft 10 beneath the tub and an operating arm 12 is rotatably mounted on the shaft 10 between the ratchet 11 and bottom of the tub as shown more particularly in Fig. 2. The end of the arm 12 is bent downwardly at 13 as shown in Fig. 2 to provide a portion 14 which extends beneath the rim 15 about the bottom of the tub and a handle 16 for moving the arm 12 is 70 secured to the portion 14 exteriorly of the tub as shown in Fig. 1. A dog 17 is pivotally mounted on the arm 12 and a coiled spring 18 is provided holding the dog 17 in engagement with the teeth of the ratchet 75 11. A tubular member 19 is secured to the shaft 10 by a pin 20 and this tubular member 19 extends about the tubular member 9 and is provided with an apertured flange 21 to which a wire basket 22 is secured. The 80 wire basket 22 is shaped so a quantity of dishes may be placed therein and the basket is rotatable by movement of the arm 12 as will be readily understood. An opening 23 is cut into the side of the tub and a member 85 24 is secured thereover by the rivets 25. This member 24 at the lower end extends on a level with the bottom of the tub and is provided with an opening 26 and a trough 27 is formed through which water may be 90 discharged from the tub. The member 24 is provided with an opening in the side thereof in which a ball 28 is adapted to fit and a socket 29 is secured to the member 24 to hold the ball in position. A pipe 30, as 95 shown in Fig. 3, extends through the ball 28 and is provided with a nozzle 31 on the discharge end thereof having conical shaped discharge apertures 32. The pipe 30 is connected to a T union 33 and a short tube 34 100 is threaded into the T union, a flexible conduit 35 being secured to the tube 34 by the clamp 36. The end of this flexible tube 35 is provided with a threaded connection 37 which may be attached to a hot or cold water faucet. A solid rod 38 is threaded into the T union 33 and a ball 39 is secured to the end of the rod 38 and provides a handle by means of which the spray nozzle may be turned in different directions through the 110 socket 29 and ball 28.

In operation the dishes to be washed are

placed in the basket 22 and the device is positioned so that the trough 27 will drain into the sink or other suitable receptacle. At this time the member 37 is connected to a 5 water faucet and the operator grasps the handles 16 and 39. By moving the handle 16 through an arc the wire basket and dishes are rotated and by means of the handle 39 and the ball and socket connection the water 10 may be directed on the different dishes in the basket 22 as they pass the spray nozzle the dishes being exposed to view through the window 5. By providing the conical apertures 32 for the spray nozzle the velocity of 15 the water passing therethrough is increased to considerable extent and the impact of the water on the surface of the dishes is of sufficient force to readily cleanse all foreign matter therefrom even when the device is 20 connected to the cold water faucet. To continuously turn the basket the handle 16 is oscillated through an arc and by means of the dog 17 and ratchet 11 the basket is turned upon each clockwise motion of the arm and 25 by grasping the handle 39 at the same time the dishes may be readily seen through the window 5 so that the water may be directed to any dish or portion of a dish desired, and by means of the operating arm 12 the 30 basket may be stopped at any point to allow any particular dish to be held under the influence of the spray nozzle. When the dishes have been washed the member 37 may be connected to the hot water faucet to allow 35 the dishes to be scalded before being removed from the machine and dried. By slotting the upper end of the shaft 10 to receive the pin 20 the basket 22 may be removed together with the tubular member 19 40 to which it is attached and the basket may be set on the sink to allow the dishes therein to drain dry or to allow drying by hand. As the water passes from the tub through the opening 26 as fast as it enters the tub 45 through the nozzle 31 the cover may be removed to allow the dishes to drain dry within the tub after the water supply has been disconnected.

From the foregoing description it becomes 50 evident that the device is very simple and efficient in operation, will not easily get out of order, is composed of few parts and is of consequent low manufacturing cost and provides a device which accomplishes the objects described.

Having thus fully described our invention, its utility and mode of operation, what we claim and desire to secure by Letters Patent of the United States is—

1. In a washing machine, a tub, a basket 60 for dishes therein adapted to be turned, the vertical wall of the tub having an offset portion terminating short of the bottom thereof providing an outlet, and a spray nozzle rotatably mounted in the said offset portion of the vertical wall and terminating practically at the periphery of the tub.

2. In a washing machine, a cylindrical tub, a basket for dishes rotatably mounted therein, the vertical wall of the said tub having an offset portion providing a recess, a spray nozzle, a ball and socket support for the nozzle in the said offset wall, the nozzle terminating adjacent the path of movement of the periphery of the basket and dishes 75 therein, a conduit for supplying water to the nozzle and means providing for a continuous discharge of liquid from the said tub.

3. In a dish washing machine, a tub, a rotatable basket therein, the wall of the said tub being offset at one side to a height above the basket, a spray nozzle mounted in the offset wall adapted to discharge fluid over and through the said basket, the said offset portion terminating short of the bottom of 80 the tub providing a discharge aperture, and a trough extending outwardly from the said discharge aperture through which fluid may be discharged from the tub.

4. In a dish washing machine, a tub having a vertical wall provided with an aperture at one side, a member adapted to be secured over the aperture providing a recess beyond the periphery of the tub, said member having a bottom portion coextensive 95 with the bottom of the tub and a substantially vertical wall terminating short of the bottom of the member providing an aperture for egress of fluid from the tub, a spray nozzle mounted for universal movement in the 100 said vertical wall of the member and terminating within the confines of the recess, a rotatable support for dishes in the tub, and means for rotating the said support to submit the various dishes to the spray from the 105 nozzle.

In testimony whereof, we sign this specification.

REDGE HARVEY.
ADOLPH P. WASHLAKE.
